Filed Mar. 13, 1970, Ser. No. 21,894

Term of patent 7 years

Int. Cl. D27—05

U.S. Cl. D48—27

FIG. 1 is a front perspective view of a cigarette lighter showing my new design;

FIG. 2 is a rear perspective view thereof;

FIG. 3 is a top plan view thereof;

FIG. 4 is a bottom plan view thereof;

FIG. 5 is a front perspective view of a second embodiment of my design;

FIG. 6 is a rear perspective view thereof;

FIG. 7 is a top plan view thereof;

FIG. 8 is a bottom plan view thereof.

The indicia is shown in broken lines in FIGS. 1, 2, 5, and 6 for illustrative purposes only. The characteristic features of my design reside in the surface ornamentation of the cigarette lighter casing.

I claim:

The ornamental design for a cigarette lighter, as shown and described.
